UNITED STATES PATENT OFFICE.

JOHN B. FREYSINGER, OF STAMFORD, CONNECTICUT, ASSIGNOR TO THE YALE & TOWNE MANUFACTURING COMPANY, OF STAMFORD, CONNECTICUT.

LOCK.

Application filed June 2, 1922. Serial No. 565,331.

To all whom it may concern:

Be it known that I, JOHN B. FREYSINGER, a citizen of the United States, and a resident of Stamford, in the county of Fairfield and State of Connecticut, have invented certain new and useful Improvements in Locks; and I do hereby declare the following to be a full, clear, and exact description of the invention, such as will enable others skilled in the art to which it appertains to make and use the same.

This invention relates to improvements in locks and more particularly to such as may be used for doors and the like,—one object of my present invention being to provide a lock having a plurality of bolts adapted to have such interlocking connection with the strike or keeper as to prevent separation of the lock casing and the keeper or otherwise picking of the lock with the use of a jimmy or other burglar's tool, and to so construct the lock that the bolts will properly and effectually interlock with the keeper without necessity for causing the lock casing to project beyond the edge of the door.

With this and other objects in view, the invention consists in certain novel features of construction and combinations of parts as hereinafter set forth and pointed out in the claim.

In the accompanying drawings; Figure 1 is a longitudinal sectional view of a lock embodying my improvements; Figure 2 is a rear face view with cover plate of the casing removed; Figure 3 is an edge view of the main bolt structure; Figure 4 is a face view of said main bolt structure; Figure 5 is an edge view of the auxiliary or dead-locking bolt structure; Figure 6 is a face view of the structure shown in Figure 5; Figure 7 is a sectional view partly in elevation showing the bolts in retracted positions, with certain parts of the operating mechanism omitted; Figure 8 is a transverse sectional view of the structure shown in Figure 7 with the bolts projected, but omitting the keeper and showing the spring for the tumbler 28, and Figure 9 is a view similar to Figure 7, but omitting the keeper and showing the bolts projected.

In the drawings I have represented my improvements with a lock of the "rim" type, but it will be understood that said improvements might be embodied in locks of other types. The casing 1 of the lock may

be secured in any suitable manner to a door so that one end thereof will lie flush with the vertical free edge of said door, and the keeper 2 may be secured to the door frame or jamb so as to be flush or in alignment 60 with the inner face of said jamb. The keeper 2 is provided at its open side with lugs or cross members 3, 3, which are so spaced apart and from the upper and lower walls of the keeper as to provide openings 65 4, 5, 6, for the passing into the keeper of bolt members carried by the lock casing as more fully hereinafter described.

The main bolt 7 of the lock comprises a plurality of bolt members 8, 9 and 10 carried by and integral with a body or apron member 11 mounted to slide on ways 12 within the casing. The body portion of the main bolt carries a talon 13 to be engaged by one or another pin 14 carried by a cross head 15 secured to the spindle 16 of a knob 17, for projecting or withdrawing the bolt. The knob spindle and cross head may be held in the position to which the same may be turned by frictional engagement of 80 spring arms 18 with said spindle as indicated in Figure 2.

The members 8 and 9 of the main bolt structure are made hollow as shown in Figures 7, 8 and 9 and as indicated by dotted lines in Figures 1 to 4, and the top wall of the intermediate bolt member 9 is provided with an opening 19, while the lower bolt member 10 is provided with a socket 20. The free ends of the several members 8, 9, 10 of the main bolt lie flush with the end 90 of the casing 1 when the main bolt is in withdrawn position and said end of the casing is provided with a plurality of openings for the passage of said bolt members.

An auxiliary or dead locking bolt structure 21, shown separately in Figures 5 and 6 of the drawings is carried by the main bolt structure and is movable transversely with relation thereto. The auxiliary bolt structure comprises a body portion 22 so associated with the body or apron portion 11 of the main bolt structure as to be movable transversely of the same, and arms 23, 24 movable in the hollow main bolt members 105 and provided with integral bolt members 25, 26, located in alignment with each other and both projecting in the same direction. The construction is such that when the main bolt is projected into the keeper, the auxiliary 110

bolt members 25, 26 will be caused to become disposed across the spaces between the main bolt members 8, 9, 10 and behind the lugs or cross members 3 of the keeper,—the free end 5 of the auxiliary bolt member 25 entering the hole 19 of the main bolt member 9 and the free end of the auxiliary bolt member 26 entering the socket 20 in the main bolt member 10. When the main bolt is in withdrawn 10 position, the arms 23—24 and the bolt members 25—26 of the auxiliary bolt structure will be housed or enclosed within the hollow members 8—9 of the main bolt structure as shown in Figure 7.

15 The body portion 22 of the auxiliary bolt structure is provided with a talon 27 with which one or the other of the pins 14 of the cross head 15 is adapted to cooperate to slide said auxiliary bolt structure trans- 20 versely of the main bolt structure after the main bolts shall have been projected or withdrawn.

25 The talon 27 of the auxiliary bolt structure carries a tumbler 28 having a lug 29 to travel in a slot 29^a in the main bolt structure when the auxiliary bolt structure is moved transversely of said main bolt structures. A 30 spring 30 serves to press the tumbler 28 rearwardly so as to cause its lug to enter an enlarged portion 31 at one end or the other of the slot 29^a and thus lock the auxiliary bolt structure in its projected position as shown in Figures 2, 8 and 9, or in its retracted 35 position with the arms 23, 24 and bolt members 25, 26 housed in the main bolt members 8 and 9 when the bolts are in retracted positions within the casing, as shown in Figure 7.

40 I have hereinbefore described knob operated means for controlling the operation of the lock, but it will be understood that key operated means may be provided also to operate the lock from the outside of the door. In Figure 1 of the drawing, I have 45 indicated a roll back cam 32 carried by the cover plate 33 of the casing for cooperation with the bolts and this cam may be operated by any suitable cylinder lock or other key operated construction, not shown, as will be 50 readily understood.

55 When the bolts 7 and 21 are in locked relation to the keeper as shown in Figure 2, they may be retracted by operation of the knob in the following manner: When the knob spindle is turned to cause movement of the pin 14 at the lower end cam or cross head 15 in the direction indicated by the arrow, said pin will operate first to depress the tumbler and move its lug 29 out of 60 locked connection with the main bolt 7 and

enter the talon 27. As said pin continues to move upwardly it will, by cooperation with said talon, cause the auxiliary bolt structure to be moved upwardly to withdraw the auxiliary bolt members 25, 26 into the hollow main bolt members 8, 9 and during such upward movement of the auxiliary bolt structure, the lug 29 of the tumbler 28 will pass upwardly through the slot 29^a and when the auxiliary bolt member 25, 26 shall 65 have been fully retracted into the main bolt members 8, 9, the tumbler lug 29 will snap into the enlarged upper end portion 31 of said slot and thus lock the auxiliary bolt members in such retracted positions. As the 70 operating pin 14 continues to move in the arc of a circle, it will engage the talon 13 on the main bolt structure and retract the latter and the auxiliary bolt structure carried thereby, into the lock casing. 75

80 Slight changes might be made in the details of construction of my invention without departing from the spirit thereof or limiting its scope as defined by the appended claim and hence I do not wish to 85 restrict myself to the precise details herein set forth.

Having fully described my invention what I claim as new and desire to secure by Letters Patent, is:— 90

95 In a lock structure, the combination with a lock casing and a keeper, of a main bolt structure mounted in the casing, an auxiliary bolt structure carried by the main bolt structure and movable transversely of the latter, said auxiliary bolt structure having bolt members having interlocking cooperation with the keeper, a spring-pressed tumbler carried by the auxiliary bolt structure and cooperable with the main bolt structure 100 to lock the auxiliary bolt structure either in retracted or projected position relatively to the main bolt structure, manually operable means cooperable with said tumbler to unlock the auxiliary bolt structure from the 105 main bolt structure and for moving said auxiliary bolt structure to projected or retracted position, and means cooperable with said manually operable means whereby operation of the latter will project or retract 110 the main bolt structure and auxiliary bolt structure relatively to the lock casing and keeper.

115 In testimony whereof, I have signed this specification in the presence of two subscribing witnesses.
